CLAIM

The ornamental design for "data storage device for use with an electronic device," as shown and described.

DESCRIPTION

FIG. 1 is a front right perspective view of data storage device.

FIG. 2 is a front view of the data storage device of FIG. 1. FIG. 3 is a right side view of the data storage device of FIG. 1.

FIG. 4 is left side view of the data storage device of FIG. 1. FIG. 5 is a top view of the data storage device of FIG. 1. FIG. 6 is a bottom view of the data storage device of FIG. 1.

FIG. 7 is a perspective rear view of the data storage device of FIG. 1; and,

FIG. 8 is a rear view of the data storage device of FIG. 1. The features shown in broken lines form no part of the claimed design.

1 Claim, 5 Drawing Sheets
